IGNITION COMPOSITION

William F. Filbert, Woodbury, N. J., assignor to
 E. I. du Pont de Nemours & Company, Wil-
 mington, Del., a corporation of Delaware

Application October 20, 1945, Serial No. 623,473

10 Claims. (Cl. 52—4)

1

This invention relates to an improved ignition composition and assembly characterized by speed and uniformity of action and other desirable properties.

It is customary, for the initiation of explosive charges, to make use of preliminary, readily ignitable compositions that can be fired by a spark or slight flame, or by the heat from an incandescent wire. Blasting caps and squibs are types of initiators employed with detonating and deflagrating explosives respectively, depending in the first case for function on the detonating impulse, and in the second case on the flame from the main initiating charge. While the explosion of charges by so-called instantaneous commercial initiators takes place with relatively great rapidity, a significant time lag invariably occurs between the first application of flame or heat and the full development of the power of the initiator.

For certain purposes where igniters are used, it is desirable that there be a very short lag and that uniformity of action should invariably result. Prior art igniters of extremely rapid action have tended to be characterized by a considerable degree of sensitiveness to electrostatic discharges. This has been particularly undesirable when igniters were used having a relatively large amount of the flame-producing charge, in order to assure ignitions of the article desired.

An object of the present invention is an improved ignition composition characterized by very rapid action and exhibiting a relatively short lag between initiation and full development of the flame. A further object is a very rapid-burning composition of the type described, which is relatively insensitive to small static charges. A further object is an ignition assembly of more than one flame-producing charge where the foregoing desirable properties are present. Additional objects will be disclosed as the invention is described in more detail hereinafter.

I have found that the foregoing objects are accomplished when I employ an ignition composition comprising a black powder type composition including a minor proportion of an added explosive ignition accelerant. While various types of black powder are applicable, desirably a finely-divided unglazed dust is used. The above composition alone is not entirely satisfactory and an initial ignition charge is desirably used with the above main charge. A complex salt of lead nitrate with a lead salt of a nitrophenol is a satisfactory ingredient of this initial charge, and preferably I use the double salt of lead nitrate

2

with a bis basic lead salt of 4,6-dinitro-ortho-cresol with a binding agent and, if desired, an oxidizing agent. This preferred double salt I shall designate as "lead salt" hereafter in this specification for purposes of simplification.

The following example of compositions and assemblies will serve to show specific embodiments of the invention. It will be understood that these are illustrative only and are not limiting in any way.

Accelerated black powder charges of the above description were prepared, the black powder itself having the composition: potassium nitrate, 74%; charcoal, 15.6%; sulfur, 10.4%. The following blends were used:

Black Powder	Accelerant, Lead Salt
Glazed—through 24, on 46—90%	10
Glazed—through 46, on 64—90%	10
Unglazed—through 46, on 64—90%	10
Dust—90% (69.1% through 150, 8.7% on 80)—98%	10 5

It was found that mixtures of the above description showed definite decrease in time of ignition, though the use of an initial ignition charge ahead of the black powder composition was desirable for satisfactory execution. The use of the very fine dust was advantageous in avoiding segregation of the different components.

For the primary ignition charge, compositions were used as follows:

Lead Salt	Potassium Chlorate	Nitro-starch	Calcium Silicide
90	—	10	—
54	—	10	—
72	27 18	10 10	9

The nitrostarch in the above compositions was used as a binding agent, gelatinization being effected by butyl acetate or other suitable volatile solvent, this solvent being removed by evaporation prior to use. The 72—27—10 composition was particularly attractive, being readily and very rapidly ignited by an incandescent wire and being capable of extremely rapid propagation of the initial firing impulse to the main black powder ignition charge. Desirably this initial charge is contained in the cavity of a bridge plug, surrounding the bridge wire.

The accompanying drawing shows the assembly of the two ignition charges. The cylindrical con-

tainer 1 has at its base the main ignition charge 2, consisting of a finely-divided black powder composition having a 5% content of the lead salt, this main charge amounting to 12 grams in weight. The leg wires 3 and 4 enter the initiator shell and are held firmly in spaced relationship with one another by the bridge plug 5. A cavity at the base of the bridge plug contains a small agglomerated initial charge 7 surrounding the bridge wire 6, and adapted to become ignited by this wire on passage of an electric current there-through. This small initial charge comprises the following composition: 72% of lead salt, 18% of potassium chlorate, and 10% of nitrostarch. When this initial charge is fired, the flame instantly ignites the main charge 2, with a very small lag between the breaking of the bridge wire and the exertion of the full igniting power of the main charge.

The main charge in the foregoing igniter is, as has been brought out, an accelerated black powder composition comprising black powder containing desirably between 1 and 25% of an explosive ignition accelerant. While various types of black powder in fine granulation may be used, it is advantageous to employ an unglazed powder of a considerable degree of fineness. Desirably the powder will be comprised of particles sufficiently fine to pass a 24-mesh screen. Even finer powder is preferable, and very satisfactory results were obtained when a powder dust was used where substantially all passed an 80-mesh screen and over 50% passed a 150-mesh screen. The use of very fine powder not only gave certain, rapid ignition but was particularly advantageous in facilitating the blending with the accelerant and preventing subsequent segregation. As such high explosive accelerant we may use various complex salts of lead nitrate with lead salts of nitrophenol, for example salts of dinitrocresols, dinitrophenols, trinitrophenols, etc. Preferably I employ the lead salt previously described and designated. Other explosive compounds may be used, however, such as mercury fulminate, diazo-dinitrophenol, and the like.

As initial ignition charge, a suitable composition comprises the double salt of lead nitrate with a lead salt of a nitrophenol, and again I find the same lead salt specifically designated very satisfactory, preferably with a binding agent and, if desired, an oxidizing ingredient. As binding agent nitrostarch may be used, a gelatinization agent such as butyl acetate or other suitable volatile solvent being employed to obtain agglomeration, the solvent being subsequently removed by evaporation. My preferred composition includes a blend of the double lead salt, potassium chlorate and nitrostarch, a satisfactory ratio being 72-18-10 for the respective ingredients.

The igniter assembly described in the foregoing possesses high utility for certain applications where unusually rapid and uniform ignition is desired. It may be used, for example, in the ignition of propellants, incendiary compositions, etc. Whereas igniters of safe characteristics previously available showed a total lag from the time the current was applied to the development of the greater part of the pressure of the main ignition charge amounting to around 30 milliseconds, the lag was reduced to around 10 milliseconds, when the igniter assembly of the present invention was used. At the same time, no hazardous condition was present with respect to accidental ignition by electrostatic discharges accumulated by operators.

The invention has been described adequately in the foregoing, but it will be understood that many variations may be introduced in the details of compositions and assemblies without departure from the scope of the invention. I intend to be limited only by the following claims.

I claim:

1. An ignition composition comprising at least 75% of a black powder composition and from 1 to 25% of an added explosive ignition accelerant consisting essentially of a primary detonating compound.

2. The ignition composition of claim 1, in which the explosive ignition accelerant is mercury fulminate.

3. An ignition composition comprising at least 75% of a black powder composition and from 1 to 25% of a complex salt of lead nitrate with a lead salt of a nitrophenol as ignition accelerant.

4. An ignition composition comprising at least 75% of a black powder composition and as ignition accelerant from 1 to 25% of a double salt of lead nitrate with a bis basic lead salt of 4,6-dinitro-ortho-cresol.

5. An ignition composition comprising at least 75% of unglazed black powder and between 1 and 25% of a double salt of lead nitrate with a bis basic lead salt of 4,6-dinitro-ortho-cresol.

6. An ignition assembly comprising (1) a main ignition charge of at least 75% of a black powder composition and from 1% to 25% of an added explosive ignition accelerant consisting essentially of a primary detonating compound and (2) an initial ignition charge comprising a complex salt of lead nitrate with a lead salt of a nitrophenol.

7. An ignition assembly comprising (1) a main ignition charge of at least 75% of a black powder composition and from 1% to 25% of an added explosive ignition accelerant consisting essentially of a primary detonating compound and (2) an initial ignition charge comprising a double salt of lead nitrate with a bis basic lead salt of 4,6-dinitro-ortho-cresol.

8. An ignition assembly comprising (1) a main ignition charge of at least 75% of a black powder composition and from 1% to 25% of an added explosive ignition accelerant consisting essentially of a primary detonating compound and (2) an initial ignition charge comprising a double salt of lead nitrate with a bis basic lead salt of 4,6-dinitro-ortho-cresol and a binding agent.

9. An ignition assembly comprising (1) a main ignition charge of at least 75% of a black powder composition and from 1% to 25% of an added explosive ignition accelerant consisting essentially of a primary detonating compound and (2) an initial ignition charge comprising a double salt of lead nitrate with a bis basic lead salt of 4,6-dinitro-ortho-cresol and nitrostarch.

10. An ignition assembly comprising (1) a main ignition charge comprising at least 75% of unglazed black powder and from 1% to 25% of an added ignition accelerant consisting essentially of a primary detonating compound, and (2) an initial ignition charge located in the cavity of a bridge plug of an electric initiating assembly, said initial charge comprising a blend of a double salt of lead nitrate with a bis basic lead salt of 4,6-dinitro-ortho-cresol, nitrostarch, and an oxidizing agent.

WILLIAM F. FILBERT.
